UNITED STATES PATENT OFFICE.

FRANK R. GROUT, OF CHICAGO, ILLINOIS.

DESIGN FOR A CASE FOR STAMP-MOISTENERS.

SPECIFICATION forming part of Design No. 30,005, dated January 17, 1899.

Application filed November 28, 1898. Serial No. 697,708. Term of patent 3½ years.

To all whom it may concern:

Be it known that I, FRANK R. GROUT, of Chicago, in the county of Cook and State of Illinois, have invented and produced a new and original Design for a Case for a Stamp-Moistener, of which the following is a specification, reference being had to the accompanying drawings, forming a part thereof.

Figure 1 is a side view of a case for a stamp-moistener, showing my design; and Fig. 2 is a sectional view taken upon the line 2 2, Fig. 1.

My design relates to cylindrical cases adapted to contain water or other liquid for the moistening of postage-stamps, envelopes, gummed labels, and the like.

As shown in the drawings, the leading or material feature of my design consists of a band *a*, in relief, said band being composed of a series of longitudinal ribs *b*, extending entirely around the cylinder midway between the ends of the cap *c*, which is mounted upon the end of the main cylinder *d* of the moistener. The ribs *b* are convex in cross-section, as shown in Fig. 2. The end of the cap is made up of two conoidal-shaped parts *e f*, the

former constituting a base and the latter emerging therefrom, as shown in Fig. 1. Upon each side of the corrugated band *a* is formed a band *g* of raised beads, the whole being interposed between plain bands *h h*. A relatively wide plain band *i*, interposed between two similar but narrower bands *j j*, is formed around the cylinder about midway between its ends. The cap *h* is preferably chased and is convex or rounded at the end, as shown. The remainder of the cylinder midway between the caps is also chased.

Having thus described my invention, what I claim as new, and desire to secure by Letters Patent, is—

The design for a case for a stamp-moistener, substantially as herein shown and described.

In testimony whereof I have signed this specification, in the presence of two subscribing witnesses, this 26th day of November, 1898.

FRANK R. GROUT.
